ART OF DEWAXING LUBRICATING OILS

Eddie M. Dons and Oswald G. Mauro, Tulsa,
Okla., assignors to Mid-Continent Petroleum
Corporation, Tulsa, Okla., a corporation of
Delaware

Application June 15, 1940, Serial No. 340,670

6 Claims. (Cl. 196—18)

This invention relates to the art of dewaxing lubricating oils, and more particularly to the separation of paraffinic wax from paraffinic oil.

Prior to this invention, petroleum lubricating oils have been dewaxed to lower the pour points of the oils and at the same time recover the wax as a valuable product. An outstanding object has been to separate all of the oil from all of the wax and this has led to the use of selective solvents or combinations of solvents intended to dissolve all of the oil without dissolving the wax.

In this industry, the fundamental and theoretically ideal object has been to remove all of the wax without including valuable lubricating oil in the wax. However, after a great deal of research and experimental work extending over many years, the industry is still seeking a feasible real solution of this fundamental problem. In some cases, misleading results appear in very large yields of oil, but such yields are likely to include a substantial percentage of wax. In other cases, absolutely wax-free oil has been obtained while a very valuable fraction of the original oil has been unexpectedly or unknowingly discarded in the wax.

Our study of this problem has shown that it is not actually solved by merely removing all of the wax, as this result can be readily accomplished while discarding some of the oil with the wax. On the other hand, the problem is not solved by merely removing all of the oil, while retaining a substantial portion of the wax in the oil. Nevertheless, these false indications of success merely add confusion to the real problem, and tend to retard continued efforts toward a real solution.

Our investigations have shown that the most aggravating phase of the real problem appears in the border line between the low melting point paraffinic waxes and the most valuable paraffinic oil. At this "border line" we find paraffinic oils and paraffinic waxes, the paraffines being so similar that the ordinary dewaxing solvents will not separate the "border line" oil from the "border line" wax. As a consequence, all of this "border line" material has appeared in either the selected oil or the rejected wax. From an economic viewpoint this is quite undesirable, as the primary object is to remove all of the wax and in the old processes this has been accomplished at the expense of discharging a substantial portion of the "border line" oil in the wax. It will be important to observe that this "border line" oil is a fraction of the highest paraffinicity, having the

highest viscosity index and, therefore, the most valuable portion of the oil.

An object of the present invention is to produce a dewaxing process wherein the dewaxing solvent will selectively dissolve not only the usual aromatic, naphthenic and paraffinic oils, but also the most valuable paraffinic "border line" oil, while rejecting the "border line" wax.

A further object is to obtain this result in an entirely feasible commercial process lacking the disadvantages likely to arise in one or more stages of such processes. More specifically stated, the process herein disclosed does not involve a critical rate of chilling, so we can obtain the advantage of rapid chilling or shock chilling, without requiring special attention to this phase of the process, and the wax crystals can be very readily separated from the oil solution. The filter rate is very high due to the low viscosity of the solution, and the entire process can be economically carried out in a very simple routine manner.

Another very important advantage appears in the flexibility or universality of the process. It can be advantageously employed to dewax all of the usual lubricating oils, including oils within the extreme viscosity ranges, and high or low paraffinic or naphthenic content, thereby providing a simple single system adapted for use in dewaxing the various lubricating distillates and residues. This eliminates the necessity of employing more than one system to efficiently dewax the various oils in a refinery, and the advantages extend to the different petroleum oils from the widely separated fields including Mid-Continent, Gulf and Pennsylvania oils.

With the foregoing and other objects in view, the invention comprises the novel process hereinafter more specifically described and shown in the accompanying drawing, which illustrates one form of the invention. However, it is to be understood that the invention comprehends changes, variations, and modifications within the scope of the claims hereunto appended.

Fig. 1 is a detail view illustrating various fractions of a body of oil, including the "border line" paraffines.

Fig. 2 is a diagrammatical view of a simple system adapted for use in carrying out the new process.

The petroleum oil to be dewaxed may be either a distillate or a residue, and it may contain some or all of the constituents set forth in Fig. 1. However, the asphaltic compounds at the bot-

tom of Fig. 1 are conveniently removed in a separate deasphalting process, and in cases where the ultimate product is a high viscosity index lubricating oil, the aromatic and naphthenic components may be removed in a separate extracting process, either before or after the dewaxing operation. However, the usual petroleum lubricating stock to be dewaxed will contain waxes of high and low melting points indicated at the upper portion of Fig. 1, and a paraffinic lubricating oil component, as well as some or all of the naphthenic and aromatic compounds.

Attention is now directed to the border line between the low melting point waxes and the paraffinic lubricating oil. Immediately above this line we find waxy paraffines in the low melting point wax, and immediately below said line we have liquid paraffines, or oil of the highest paraffinicity. This portion of the paraffinic oil has the highest viscosity index, and it is the most valuable part of the lubricating oil. However, it consists of paraffines similar to the paraffines in the low melting point wax, and the old dewaxing problem appears in selectively dissolving this oil of highest paraffinicity, without dissolving the similar paraffines in the wax.

Briefly stated, the present invention involves the use of a combination of solvents which select and recover all, or a substantial part, of the "border line" paraffinic oil. This oil is separated from the "border line" wax and recovered in the body of dewaxed oil, thereby selectively separating approximately all of the desired lubricating oil from the wax content of the original oil. To accomplish this result we employ a combination of solvents, each having a low solvent power for wax and relatively high solvent powers for the various paraffinic, naphthenic and aromatic oils.

In the preferred form of the invention, one of these solvents is isopropyl acetate, a very poor wax solvent but a good naphthenic oil solvent and a moderately good paraffinic oil solvent. The other selective solvent is methylene dichloride, a poor wax solvent, but a very good paraffinic oil solvent, and a moderately good naphthenic solvent. When either of these solvents is used alone, it would fail to accomplish the desired results, but when said solvents are combined with each other as hereinafter set forth, they provide the specific conditions necessary to first dissolve all of the constituents of the original oil, and thereafter selectively dissolve the oil fractions including approximately all of the "border line" paraffinic oil, without dissolving the similar paraffines in the "border line" wax. We believe that it is practically impossible to dissolve every trace of this "border line" oil without dissolving some of the wax, but very substantial commercial advantages are gained by any improvement over the conventional industrial dewaxing operations, wherein the selective solvents fail to adequately control the selection of highly paraffinic oil at the border line.

Fig. 2 is an illustration of a conventional dewaxing system adapted to carry out one form of the invention. In this view, 3 designates a storage tank for the oil to be dewaxed; 4 indicates a tank containing methylene dichloride, and 5 is a tank for isopropyl acetate. A stream of oil is pumped through a line 6 to a conductor 7, while streams of methylene dichloride and isopropyl acetate are pumped through lines 8 and 9, respectively, to a line 10 which leads to the conductor 7. The merged streams of solvents and oil may be transmitted to a heater 11 and thence through

5 a mixer 12 to a cooler or chiller 13 where the solution is chilled to precipitate the wax. The resultant chilled mixture may be transmitted through a line 14 to a receptacle 15 containing a rotary filter 16. If this filter is of the vacuum type, the dewaxed oil solution passing through the filtering material will be discharged through a central pipe 17, while the wax will be deposited on the peripheral surface of the filter. This layer of wax may be removed at a stationary scraper 18 and discharged to a screw conveyor 19.

To very effectively wash oily solution from the layer of wax on the rotary filter 16, methylene dichloride alone may be pumped through a line 20 to a cooler 21 and thence to a spraying device 22 immediately above the filter. This methylene dichloride is preferably at a temperature substantially higher than the temperature of the wax. More specifically stated, if the solution is dewaxed at about 0° F. the temperature of the shower of methylene dichloride may be about 20° F., so as to very effectively dissolve and wash the oily solution from the layer of wax, the resultant solution being transmitted through the wax so as to enter into the dewaxed oil solution.

As a specific illustration, we will refer to the dewaxing of a reduced crude oil having a Saybolt Universal viscosity of 150 at 210° F., and using a solvent blend comprising 40 per cent isopropyl acetate and 60 per cent methylene dichloride. When employing about five volumes of this solvent blend to one volume of the oil charge, the dewaxing may be performed at about 15° F. 30 to obtain a dewaxed oil having a pour point of about 10° F. to 15° F. About one-half of a volume of methylene dichloride may be showered onto the layer of wax carried by the filter.

However, the proportions of the solvents may 40 be varied as desired to meet different conditions. Oils of the highest paraffinicity require more methylene dichloride than oils of lower paraffinicity, and the viscosity of the oil is another factor in determining the proportions of methylene dichloride and isopropyl acetate. However, in dewaxing the various products, the isopropyl acetate preferably forms more than 25 per cent of the solvent blend, while the methylene dichloride is less than 75 per cent.

50 In the preferred form of the invention, the solution is heated to, for example, 120° F., and then chilled to a temperature at which the isopropyl acetate and methylene dichloride will selectively dissolve approximately all of the oil of highest paraffinicity without dissolving a substantial volume of similar paraffines in the wax component. The selected oil solution is then separated from the undissolved wax. The resultant product is a lubricating oil having a low pour point, and a 55 relatively high viscosity index due to the recovery of the most paraffinic oil which ordinarily remains with the similar waxy paraffines.

We claim:

65 1. In the art of dewaxing petroleum lubricating oil having paraffinic oil components and similar paraffinic wax components, the process of separating said similar paraffinic components which comprises dissolving said petroleum oil in a solvent comprising isopropyl acetate and methylene dichloride, chilling the solution to a temperature at which said solvent will selectively dissolve approximately all of the oil of highest paraffinicity without dissolving a substantial volume of similar paraffines in the wax component.

and separating the selected oil solution from the undissolved wax component.

2. In the art of making lubricating oil having a low pour point and a high viscosity index, the process of selecting and separating the paraffinic oil component of highest viscosity index from similar paraffinic waxes which comprises dissolving a wax-bearing petroleum oil in a solvent comprising isopropyl acetate and methylene dichloride, chilling the solution to a temperature at which the isopropyl acetate and methylene dichloride will selectively dissolve approximately all of the oil of highest paraffinicity without dissolving a substantial volume of similar paraffines in the wax component, and separating the selected oil solution from the undissolved wax component.

3. In the art of dewaxing petroleum lubricating oil, the process of selecting and separating the most paraffinic lubricating oil from similar paraffines in low melting point paraffinic waxes which comprises dissolving the wax-bearing petroleum oil in a solvent comprising isopropyl acetate and methylene dichloride, chilling the solution to approximately a temperature at which said solvent will selectively dissolve substantially all of the paraffinic lubricating oil constituents without dissolving said similar paraffines in the low melting point paraffinic waxes, and separating the dissolved oil from the waxes.

4. In the art of dewaxing petroleum lubricating oil having aromatic, naphthenic and paraffinic oil components and a low melting point paraffinic wax component, the process of separating said paraffinic oil component from similar paraffines in the low melting point wax component which comprises dissolving said petroleum oil in a solvent comprising isopropyl acetate and methylene dichloride, chilling the solution to approximately a temperature at which the isopropyl ace-

tate and methylene dichloride will selectively dissolve said oil components, including approximately all of the oil of highest paraffinicity, without dissolving similar paraffines in the low melting point wax component, and separating the selected oil solution from the wax.

5. In the art of separating petroleum oils and waxes, the process which comprises dissolving the oil and wax in a solvent comprising more than 25 per cent isopropyl acetate and less than 75 per cent methylene dichloride, cooling the solution to a temperature at which the isopropyl acetate and methylene dichloride will selectively dissolve the oil and reject the wax, and separating the selected oil solution from the rejected wax.

6. In the art of dewaxing petroleum lubricating oils, the process of deliberately separating unitary border line paraffines consisting of the most paraffinic lubricating oil constituents united with similar paraffines in low melting point waxes, said process including the steps of dissolving the wax-bearing oil in a solvent blend comprising isopropyl acetate combined with a predetermined quantity of methylene dichloride having a higher solvent power for paraffines, cooling the solution to a predetermined temperature, and separating the selected oil solution from the wax, said predetermined quantity of methylene dichloride being sufficient to cooperate with the isopropyl acetate in selectively dissolving substantially all of most paraffinic lubricating oil constituents without dissolving said similar paraffines in the low melting point wax at said predetermined temperature, so as to positively separate said unitary border line paraffines and at the same time transfer said most paraffinic oil constituents to the oil solution.
